US0D1057337S

(12) **United States Design Patent** (10) **Patent No.:** **US D1,057,337 S**
(45) **Date of Patent:** **** Jan. 7, 2025**

(54) **FLOOR CLEANING WIPE**

(71) Applicant: **The Procter & Gamble Company**,
Cincinnati, OH (US)

(72) Inventor: **Nicola John Policicchio**, Mason, OH
(US)

(73) Assignee: **The Procter & Gamble Company**,
Cincinnati, OH (US)

(**) Term: **15 Years**

(21) Appl. No.: **29/825,118**

(22) Filed: **Jan. 28, 2022**

(51) LOC (15) Cl. **07-05**

(52) U.S. Cl.

USPC **D32/40**

(57) **CLAIM**

The ornamental design for a floor cleaning wipe as shown and described.

DESCRIPTION

FIG. 1 is a perspective view of an embodiment of a floor cleaning wipe;

FIG. 2 is a top view of the floor cleaning wipe shown in FIG. 1;

FIG. 3 is a side view of the floor cleaning wipe shown in FIG. 1;

FIG. 4 is a bottom view of the floor cleaning wipe shown in FIG. 1;

FIG. 5 is a side view of the floor cleaning wipe shown in FIG. 1 and opposite the side view shown in FIG. 3;

FIG. 6 is side view of the floor cleaning wipe shown in FIG. 1;

FIG. 7 is a side view of the floor cleaning wipe shown in FIG. 1 and opposite the side view shown in FIG. 6.

FIG. 8 is a perspective view of an embodiment of a floor cleaning wipe;

FIG. 9 is a top view of the floor cleaning wipe shown in FIG. 8;

FIG. 10 is a side view of the floor cleaning wipe shown in FIG. 8;

FIG. 11 is a bottom view of the floor cleaning wipe shown in FIG. 8;

FIG. 12 is a side view of the floor cleaning wipe shown in FIG. 8 and opposite the side view shown in FIG. 10;

FIG. 13 is side view of the floor cleaning wipe shown in FIG. 8;

FIG. 14 is a side view of the floor cleaning wipe shown in FIG. 8 and opposite the side view shown in FIG. 13.

FIG. 15 is a perspective view of an embodiment of a floor cleaning wipe;

FIG. 16 is a top view of the floor cleaning wipe shown in FIG. 15;

FIG. 17 is a side view of the floor cleaning wipe shown in FIG. 15;

(Continued)

FIG. 18 is a bottom view of the floor cleaning wipe shown in FIG. 15;

FIG. 19 is a side view of the floor cleaning wipe shown in FIG. 15 and opposite the side view shown in FIG. 17; FIG. 20 is side view of the floor cleaning wipe shown in FIG. 15; and,

FIG. 21 is a side view of the floor cleaning wipe shown in FIG. 15 and opposite the side view shown in FIG. 20. The dashed broken lines illustrate structure or features that form no part of the claimed design. The dot-dash broken lines define the bounds of the claimed design and form no part thereof.

The grayscale shading illustrates contrasts in color and particular shades do not correspond to any particular color.

1 Claim, 9 Drawing Sheets

(58) Field of Classification Search

CPC A47L 15/48; A47L 15/481
